CONTAINER

George W. Blair, Mishawaka, Ind., assignor to
 United States Rubber Company, New York,
 N. Y., a corporation of New Jersey

Application December 30, 1942, Serial No. 470,699

2 Claims. (Cl. 150—0.5)

This invention relates to containers for storing liquids, particularly gasoline and oil for internal combustion motors, distilled water for storage battery installations and the like.

It is usual at airports and other places where large quantities of motor fuel must be kept, to store gasoline in large metal tanks containing thousands of gallons and disposed either above or below the surface of the ground. Such tanks and their accompanying piping require large numbers of skilled workmen for their installation and when installed are more or less permanent. They cannot readily be moved. In military operations it is important to be able readily to transport facilities for the storage of large quantities of gasoline or other liquids, and to set up such facilities quickly with a small number of unskilled persons.

The present invention provides means for accomplishing this objective by providing light, flexible, collapsible tanks or storage containers which are capable of holding relatively large quantities of motor fuel and which can be readily transported and set up. In accordance with my invention I provide a liquid retaining element in the form of a large flexible container in which a relatively small quantity of impervious material is used, and I provide a separate means, which may be an outer container, which surrounds and supports the side wall of the liquid container and thus supports the hydrostatic forces of the confined liquid, relieving the impervious container of all stresses due to the weight of the liquid it contains. In this manner a light and easily transported fuel storage container is provided having a minimum quantity of impervious material, the outer or supporting means being made of readily available inexpensive materials which need not be impervious or inert to the fuel.

In the accompanying drawing:

Fig. 1 is a perspective view of one form of fuel storage container embodying the invention;

Fig. 2 is a vertical section of the container corresponding to the line 2—2 of Fig. 1; and

Fig. 3 is an enlarged vertical section of a portion of a container showing a connection plate for the attachment of conduits.

The fuel storage container includes a closed cylindrical container 10 which forms an impervious fuel containing element, and which is disposed in an outer cylindrical side wall 12 which furnishes the support for the weight of the fuel. The wall 12 is preferably the side wall of an open-topped cylindrical container of textile fabric of high tensile strength. The inner

container is formed of a light-weight, flexible, substantially inelastic material which is both inert and impervious to the liquid to be stored. Preferably the material is inert to aromatic hydrocarbon fuels. An example of such material is light weight textile fabric impregnated with a suitable synthetic rubber or rubber-like composition such as the olefin polysulphide plastic material known in the trade as Thiokol. Preferably fabric impregnated with the inert material is cut to proper shape and size and the pieces are cemented or vulcanized together with or without sewing to form a closed cylinder of desired size, all joints being rendered impervious to the liquid to be stored in any suitable manner known in the art.

The inner container has a circular bottom wall 14 and a circular top wall 16 joined by a cylindrical side wall 18. The cylindrical side wall and the upturned edge of the top 16 preferably extend above the top to form a flange 19 to which loops of fabric 20 are attached to facilitate handling and to provide supports for the side wall as will be explained.

The inner container may be filled, drained, and vented by suitable conduits preferably all attached to a single plate or support as illustrated best in Fig. 3. The top wall 16 has a single opening 21, the edge of which is reinforced by a grommet comprising a metal ring 22 and washers 23. A plate 24 is attached to the grommet by any suitable device such as screws 26. Suitably attached to the plate are any desired conduits, for example a vent pipe 28 and a pipe 30 which extends to the bottom of the container and which serve both to fill and to empty the container. The pipe 30 is flexible, for example, being formed of a Thiokol hose, so that the inner container can be collapsed and rolled up without danger of injury.

The weight of the inner container, filled with liquid, is supported by the outer container, and in order to transmit all forces to the outer container and prevent any stresses in the fabric of the inner container which tend to rupture it, the diameter of the inner container is made slightly larger than the diameter of the outer container and the side wall of the outer container is at least as tall as the side wall of the inner container. When the inner container is placed in the outer container and filled, the inner container wrinkles slightly as indicated in Figs. 1 and 2 assuring that the corner of the outer container where the side wall joins the bottom, is completely filled with liquid and there are no

tension stresses in the fabric of the inner container.

The outer container is in the form of an open ended cylinder of textile fabric of high tensile strength comprising a circular bottom 40 to which the cylindrical side wall 12 is sewed. The diameter of the outer container is slightly less than the diameter of the inner container as explained above. The side wall 12 has a number of sleeves or patches 44 sewed to it, which receive flat posts or struts 46 which are held together in a circle by the tension of the side wall and patches 44, and if desired by ropes 48. The posts are held outwardly against the tension of the side wall and ropes by radial tension elements such as ropes 50 secured to stakes 52. The side wall 12 is suspended from the notched upper ends of the struts 48 by ropes 54. This arrangement supports the side wall as an upright cylinder whether or not the inner container is filled.

Where it is desired not to have the inner container collapse when empty, the top 16 is supported from poles 56 by ropes 58 attached to fabric tabs or patches cemented to the top wall 16. The poles 58 are suitably supported on appropriate struts 46. Also the tabs 20 on the upper flange 19 of the inner container may be suspended by ropes 59 from appropriate struts 46.

The invention thus facilitates storing of large quantities of liquids in relatively inexpensive containers which may be transported and set up quickly by unskilled persons with a minimum of simple tools. It also permits the storage of large quantities of aircraft fuel in containers requiring relatively small quantities of inert or impervious material because the inner container supports no weight and therefore can be made of very light material, merely strong enough to support its own weight and withstand handling.

Having thus described my invention what I desire to protect by Letters Patent is:

1. A liquid storage container comprising in combination an open-topped outer container formed of textile fabric and including a circular bottom wall and a cylindrical side wall attached thereto, a plurality of rigid vertical supports disposed about the side wall, means for suspending the side wall from the vertical supports, an inner container formed of flexible substantially inelastic impervious material and comprising a circular bottom wall and a circular top wall connected by a cylindrical side wall, the normal diameter of the inner container when unconfined being greater than the diameter of the outer container, horizontal supports supported by the vertical supports above the top of the inner container and means for supporting the top of the inner container from said horizontal supports.
2. A liquid storage container comprising in combination an open-topped outer container formed of textile fabric and including a circular bottom wall and a cylindrical side wall attached thereto, a plurality of rigid vertical supports disposed substantially in a circle adjacent the side wall, tension means connecting the supports circumferentially, tension means urging the supports radially outward, means for supporting the side wall of the outer container on said supports and an inner container formed of flexible, inelastic impervious material and comprising a circular bottom wall and a circular top wall connected by a cylindrical side wall, the inner container being disposed inside the outer container and the diameter of the inner container when unconfined being greater than the diameter of the outer container.

GEORGE W. BLAIR.
